THE COLUMBIA PLANOGRAPH CO., WASHINGTON, D. C.

UNITED STATES PATENT OFFICE.

NERI MARTINI BERNARDI, OF FLORENCE, ITALY.

SCREW-WRENCH IN WHICH NO DETRIMENTAL PLAY CAN OBTAIN.

1,313,575.

Specification of Letters Patent. Patented Aug. 19, 1919.

Application filed June 13, 1917. Serial No. 174,464.

To all whom it may concern:

Be it known that I, NERI MARTINI BERNARDI, subject of the Kingdom of Italy, residing at Florence, Italy, have invented 5 new and useful Improvements in Screw-Wrenches, in which no Detrimental Play Can Obtain, of which the following is a specification.

My invention relates to that class of 10 wrenches provided with a stationary jaw and a sliding jaw.

An object of my invention is to provide means, whereby the sliding jaw will be, on operation, firmly, rapidly and durably 15 blocked in position.

To this effect, the means I propose consists essentially of tapered blocks capable of being rapidly, materially and frictionally counteracted relative to any dangerous play 20 of the sliding jaw.

The invention comprises, in addition, new arrangements of parts as will be fully described hereafter.

In the annexed drawings are illustrated 25 several forms of construction of my invention.

Figure 1 is an elevational side view, partly in section of a first form of construction of the improved nut-wrench.

30 Fig. 2 is an elevational front view of the same.

Fig. 3 represents a section on line 3—3 of Fig. 1.

Fig. 4 represents a section on line 4—4 of Fig. 1.

Fig. 5 is an elevational side view of a second form of construction of my nut wrench.

Fig. 6 is a sectional front view of the same.

40 Fig. 7 represents a section on line 7—7 of Fig. 5.

Figs. 8, 9, 10 represent in the same way as Figs. 4, 5, 6 a third form of construction of my improved wrench.

45 Fig. 11 is a sectional view taken on the line 11—11 of Fig. 8.

Figs. 12, 13, 14, 15, 16, 17 represent details of modified parts of my wrench.

Fig. 18 is an elevational side view, partly 50 in section of a fourth form of construction.

Fig. 19 is an elevational front view of same.

Figs. 20 and 21 represent in elevation and plan-view a detail of said fourth form.

55 Fig. 22 is a section on line 22—22 of Fig. 19.

Fig. 23 is a section on line 23—23 of Fig. 19.

Figs. 24 and 25 represent in elevation and plan-view a modified form of the detail as 60 shown in Figs. 20 and 21.

Fig. 26 is a side sectional view of a fifth form of construction of the wrench.

Fig. 27 is a front sectional view of the same. 65

Fig. 28 represents a plan view of the stationary jaw in said fifth form of construction.

Fig. 29 represents a section on line 29—29 of Fig. 26. 70

Fig. 30 represents a section on line 30—30 of Fig. 26.

Fig. 31 is a side view, partly in section of a sixth form of construction of the wrench. 75

Fig. 32 is a side sectional view of a seventh form of construction of the improved wrench.

Fig. 33 is a front sectional view of same.

Fig. 34 is a section on line 34—34 of 80 Fig. 32.

Like reference numerals represent similar parts throughout the drawings.

Referring first to the form of construction represented in the Figs. 1—2—3—4, the 85 wrench comprises a stationary jaw *a* and a slidible jaw *b*, said jaw *a* being fixed to the end of a shank *n*, said slidible jaw *b* being slidably fitted on said shank and guided by the square side ribs *o* of said shank which 90 fit into corresponding side-slots *p* (Fig. 2) forming parts of a cavity in the jaw body.

The end walls of said cavity are inclined and form with the end walls of shank *n*, two wedge-like sockets to receive the blocking-device; said blocking device consisting of one or two wedges *c*, *d* forming the ends of a fork *l*, conveniently arranged on said shank, by way of two branches fitted in grooves *m* recessed along the back and front 100 walls of the shank.

Fork 1, being thus capable of reciprocating on the wrench-shank, is provided with a governing spindle having a thread *h* and a thread *g*, thread *h* being screwed to the shank and thread *g* being screwed to the 105 head of fork *l*. The spindle may be rotated by hand, through a handle *k* or the like, fastened to the outer end of said spindle by means of a pin *i*.

In operation, the stationary jaw *a* being set against a face of the nut, jaw *b* will be 110

brought, by hand, against the opposite face. On rotating the spindle *h*, *g*, the shank *n* and the fork will be relatively moved whereby the wedges *c-d* will be forced between 5 the jaw and shank, thus securing a tight and durable hold of the nut.

In the form of construction represented in Figs. 5, 6, 7, besides the blocking means, there are arranged setting means for a fine 10 adjustment of the wrench.

The wrench comprises a stationary jaw 1 and a slidable jaw 4, said slidable jaw being guided on the ribs 5 of the shank 2 and offering tapered sockets to the wedge-like ends 15 13, 14 of a fork 12. The jaw-body 4 is connected by a pivot 8 to one end of a rack 7, said rack being slidably located in a slot 6, said slot formed in one side of the shank 2.

Rack 7 is worked by means of a worm 9 20 pivoted and carried by a side plate 10, which, together with side plate 11, is arranged laterally of the middle wrench-portion and forms with the sides of the shank 2 the necessary grooves for the guidance of 25 fork 12.

The shank 2 has a threaded end 3 screwed to an internally threaded sleeve 16, said sleeve being provided with a muff-like handle 15 and fitted in a hub-like head 17 of the 30 fork 12; the sleeve being longitudinally rendered immovable relative to the fork by a locking screw clearly shown in Fig. 6.

In operation, a preliminary adjustment of the wrench is secured by rotating, by hand, worm 9; whereupon the further and final setting of the jaws is caused by the rotation of muff-handle 15, which forces jaw 1 toward jaw 4; a tight hold of the nut being thus secured.

40 The form of construction given in Figs. 8, 9, 10 and 11, represents a slight modification of the previously described types.

The construction of jaw 1, shank 2 and screw 3 remains unaltered. The two wedges 45 13 and 14 form part of a casing 18 for the shank 2. At its lower portion, said casing widens so as to enable the attachment, by means of screws 19 or the like, of a socket 20, within which plays a sleeve 16 fastened 50 to a handle 23 by means of a nut 21 and key 22.

In such wrench-form, the jaw 4 is set by rotating the handle 23, thus moving the casing 18 toward the jaw 4 and thereby causing 55 the wedges 13 and 14 to lock the jaw 4, as will be understood.

Of course even such type might be provided with a racking device as described above.

60 In order to avoid an unnecessary play of the sliding jaw, a spring 24, lodged in a recess of the jaw-body, may be provided.

The blocking wedges may be formed separately from the casing 18 and mounted 65 thereon as shown in Fig. 12; or, as shown in

Fig. 13, one wedge only 25 may be employed.

Also, as shown in Figs. 14 and 15, the shank 2 may be circular in section, in which case the cavity of the jaw-body takes the 70 form of a cone and the blocking pieces 13-14 take the form of cone-portions; or, as shown in Figs. 16 and 17, the blocking device may take the form of a whole cone as shown in detail by Figs. 16 and 17. In forms 75 of these kinds a guiding slot should be provided, as, for example, shown in Figs. 15 and 17.

Referring now to the form of construction represented in Figs. 18, 19, 20, 21, 22 and 23, 80 the wrench has a round shank 2 provided with longitudinal groove 29. Jaw 40 bears a projection 41, which enters partially the groove 29 and forms the guiding means 27 of the jaw. A small stop-spring 42 is located in the back portion of said projection 41.

The cavity of the sliding jaw-body is conical in form and receives a blocking-cone 30 forming the upper end of a sleeve 28. 90

Said cone is preferably slotted along four generating lines, whereby an elastic combination of segments 31, 32, 33, 34 is obtained, as shown in detail in Figs. 20 and 21.

The lower portion of sleeve 28 is externally threaded and is screwed to a sleeve 35, which at its lower end turns freely on a reduced lower portion 36 of shank 2. Also on the portion 36 are a holding cap 37 and a fastening nut 39, the former keyed as shown 100 at 38.

The operation of such form of wrench is effected by manually turning sleeve 35 as already set forth in the description of other forms.

105 In Figs. 24 and 25, representing in elevation and plan a modified form of the construction of Figs. 20 and 21, the shank 2 is shown as having a pair of wedge blocks 43 and 44; in Fig. 25 the sleeve 35 of Fig. 19 being illustrated in place on the cylindrical lower portion of shank 2.

In the form of construction of the Figs. 26, 27, 28, 29 and 30, a sleeve 28' extends the whole length of the wrench and is internally 115 threaded and is screwed to an externally threaded portion 46 formed on the lower end of a shank 2' carrying the fixed jaw 1, a cap 51, secured in place by a pin 52, closing the lower end of sleeve 28'. The sliding-jaw cavity is preferably conical, to receive the slotted conical blocking piece 30^a. There

120 are guiding slots 29 in shank 2' to receive flat projections 47 and 48 of the movable jaw-body 40. A spring 49 forms, with a slide-piece 50 working on the back of jaw 1, a frictional connection between jaw 1 and jaw 40, in order to prevent an undesired slipping of jaw 40 along shank 2, when the wedge 30^a is being loosened.

The form of Fig. 31 is a slight modification of form Fig. 27. The sleeve 28 is shortened and shank 2 is prolonged beyond the threaded portion 46.

5 In the form of construction given in Figs. 32, 33 and 34, the wedges 13 and 14 are pivoted at 53 and 54 on sleeve 18, said feature allowing displacements of the jaws which is necessary in certain instances during the working of the wrench.

The shank has two grooves 55 and 56 to receive guiding flats 57 and 58 on jaw 4; there being a stop spring 59, located between jaw 4 and slot 56, in a small recess 15 of flat 58.

For the remaining part, said wrench is of the same description as the construction of Figs. 8 and 9.

Having thus fully described my invention 20 I claim:

1. A wrench comprising, in combination, a stationary jaw having a shank, guiding grooves and guiding ribs on said shank, a 25 slideable jaw having a tapered cavity and guiding grooves for the said guiding ribs, a fork-like member with a wedge-shaped end structure, said wedge structure entering the cavity of said jaw to block it in position, and means to force said member toward 30 said jaw-cavity.

2. A wrench comprising, in combination, a stationary jaw having a shank, guiding grooves and guiding ribs on said shank, a 35 slideable jaw with a tapered cavity and guiding grooves for said guiding ribs, a rack pivotally connected to said sliding jaw, a worm gearing with said rack and pivoted on said shank, a fork-like slider having wedged-ends, and means to cause said slider to recip- 40 rocate on said shank.

3. A wrench comprising, in combination, a stationary jaw having a shank, guiding grooves and guiding ribs on said shank, a 45 slideable jaw with a tapered flat faced cavity and guiding grooves for said guiding ribs, a wedged fork-slider mounted on said shank, a rack connected to said sliding-jaw and slidably fitted on one side of said shank,

a worm gearing with said rack and pivoted on said shank, a screw-thread on the end of 50 said shank, and internally threaded sleeve on said screw-thread, said sleeve carrying a handle and being rotatable but restrained against axial movement relative to the fork for forcing the fork into the sliding jaw 55 cavity to block it in position.

4. A wrench comprising, in combination, a stationary jaw having a shank, guiding grooves and guiding ribs on said shank, a 60 slideable jaw with a conical cavity and guiding grooves for said guiding ribs, a rack connected to said sliding jaw and slidably fitted on one side of said shank, a worm gearing with said rack and pivoted on said shank, a screw thread on the end of 65 said shank, and a fork slider having two conical wedges at one end and a sleeve member at the other end, and means, including said screw thread to cause said fork-slider to reciprocate on said shank. 70

5. A wrench comprising, in combination, a stationary jaw having a shank, a sliding jaw having a tapered cavity, a rack connected with said sliding-jaw, a worm gearing with said rack, a casing for the shank and having 75 an enlarged portion at one end and two wedges at the other end, and means for moving said wedges along said shank including a socket carried by the casing, and a sleeve rotatable in said socket and opera- 80 tively connected to the shank.

6. A wrench comprising a stationary jaw having a shank, a sliding jaw having a tapered cavity to receive the shank, wedges disposed upon the opposite edges of the 85 shank adapted to work in the cavity, and means for actuating the wedges to lock the sliding jaw against movement.

In testimony whereof I have signed my name to this specification in the presence 90 of two subscribing witnesses.

NERI MARTINI BERNARDI.
